SHORTHAND TYPEWRITING MACHINE

John L. Stixrud, Los Angeles, Calif.

Application January 13, 1945, Serial No. 572,588

11 Claims.

(Cl. 197—9)

1

This invention relates to certain new and useful improvements in typewriting machines and deals particularly with that type of machine which is directed to phonetic writing whereby the spoken language may be rapidly typed without the use of codes to represent the missing letters.

The present invention embodies the broad principles outlined in my co-pending application filed November 8, 1943, Ser. No. 509,514 but includes certain modifications and structural details by which a marked improvement in the operation of the machine will be noted.

The primary object of the present case resides in the simple yet efficient manner of initially selecting and then subsequently printing the selected character upon the depression of the characterized key.

A further object resides in the mechanical connections between the back keys and the movable printing members by which the printing members are properly positioned upon the depression of the selected key.

A still further object of the invention resides in the novel manner of arranging the several keys on horizontal pivots whereby a tilting action may be had to make the various selections of the desired characters and then to cause a printing of the character when the key is fully depressed.

Another object of the invention resides in the novel manner of coupling the action of two of said keys to accomplish the printing of certain characters.

A further object of the invention resides in the novel arrangement of letters and characters to be printed.

These and other objects will readily be presented to those skilled in this particular art, when the following specification is read in connection with the attached drawings, wherein like parts are designated by similar reference characters throughout the several views.

In the drawings I have illustrated the preferred embodiment of my invention, but it is to be understood that certain variations therefrom may be resorted to without sacrificing any of the spirit of the present invention.

In the drawings:

Fig. 1 shows a plan view of the machine, omitting certain parts to show underlying construction.

Fig. 2 is a side view with parts of the frame broken away to more clearly illustrate some of the detailed parts of the mechanism.

2

Fig. 3 is a sectional view taken on line 3—3 of Fig. 2.

Fig. 4 is a fragmentary sectional view taken on line 4—4 of Fig. 2.

Fig. 5 is an elevational view showing an exaggerated forward position of the pivotal connections between the printing members and the parts which actuate them.

Referring more in detail to the drawings, 10 designates side frame plates, each having leg portions 11—11 by which the machine is supported. Each leg may be offset as at 12 with an aperture 13 therein to which rubber cushions or feet may be fastened.

Rotatably mounted between the frame plates 10 at the far end of the machine is a platen 14 which supports the paper or other strip material upon which the printing is to be accomplished. Directly in front of the platen 14 is a series of printing members 22, each having an arcuate face, bearing type characters designated 15, 16, 17, 18 and 19. These printing members are actuated from keys positioned at the front of the machine through the medium of longitudinally extending connecting bar members. In view of the fact that each printing member is actuated in a like manner a description of the operation of one will be sufficient for a clear understanding of the complete operation of the machine.

Each printing member 20 is pivotally connected by means of pins 21 and 22 to the upper ends of arms 23 and 24 respectively. Pin 22 works in a vertically disposed slot 22a in the arm 24. The purpose of the slot 22a is to permit the arm 24 to move at a slower speed than the arm 23. As will be noted the arm 24 is slightly longer than the arm 23, this being for a purpose hereinafter described. The arm 23 has a forwardly extending finger 25 while the arm 24 has a slightly longer finger 26. Each finger and arm construction just described constitutes a bell crank lever which is pivotally mounted on the cross shaft 27 supported between the frame plates 10—10.

A cross rod 28 is also mounted within the side frame plates 10—10 and is spaced forwardly in parallel relation to the cross shaft 27. Pivotally mounted on the cross rod 28 are a series of pairs of key bars, said bars being designated 29—30.

Each bar 29—30 has a relatively short finger extension as shown at 31 and 32 respectively. The finger 32 which connects with the finger 26 is slightly shorter than 31 in order to impart a slower motion to the arm 24 and thus cause a horizontal movement of the printing member 20.

when the pair of key bars 29-30 are rocked simultaneously.

Attached to the upper portion of each of the arms 23 and 24 is a spring 33 and 33a, the opposite end of each spring being respectively fastened to the hooks 34 and 34a which are carried by a cross bar 35. The tension of the springs 33-33a results in the return of the operating bars to their normal set position after each operation. The key bars are limited in their return movement by a pad element 36 which is carried by the cross support 37.

The pivotally mounted bell crank levers on the cross shaft 27 are separated by spacers 38 and also the bar elements which are pivotally supported on the cross rod 28 are separated by spacers 39.

The key bars 29 and 30 each have a T shaped arm extending upwardly from their forward end. The adjacent inner ends of these arms are arranged in overlapping relation as suggested at 40 and 40a. The opposite ends of these T arms are formed with a bevelled upper surface 41-41a. The medial portions of these T arms have a flat surface as indicated at 42-42a. Key plates 43-43a are pivotally attached as suggested at 44-44a to the T arms so that they normally rest on the flat surfaces 42-42a. The under surface of each key plate 43-43a which overhangs the bevelled surfaces 41-41a may be padded with a sound reducing material. The overlapping ends 40-40a extend beneath the key plates 43a and 43 of the opposite key bar.

As will be noted from the illustration suggested in Fig. 1 the key plates 43 and 43a are attached to the upper ends of the key bars 29 and 30 and are arranged in two rows designated A and B. In advance of these rows A and B there is also shown a third row as indicated at C. These last mentioned keys are coupled together transversely instead of longitudinally as suggested in keys A and B, but their action is practically the same in the operation of the typing members.

The key bars leading to the keys in row C are designated 46-47. The forward ends of these bars have an upwardly extended portion 48 upon which a key 49 is pivotally mounted at 48a. The upper surface of the portion 48 forward of the pivot is bevelled as at 50.

The bar 46 has an angular extending arm 51 while the bar 47 is bent as indicated at 52. The keys are each provided with a forwardly projecting arm 53 which extends over the angular arm 51 and the bent portion 52. The bar 47 is widened at 54 with a flange 55 at the upper end and a flange 56 at the lower edge, as shown in Fig. 3. The bar 46 has an inwardly directed bearing 57 which is positioned medially between the flanges 55 and 56.

The general operation of the machine is as follows: The initial movement of the key bars merely causes a movement of the printing member to select the character to be printed and the final downward portion of the bar movement couples the adjacent bar to cause a forward movement of the printing member which results in the printing of the character. A more detailed description of the operation is as follows.

Any of the characters in the first line of row A of the keys may be printed by depressing the key plate at a point directly above the character. This results in the pivotal movement of the key plate and when the plate contacts with the bevelled surface of the key bar, that particular key bar starts downward movement which causes

the printing member to swing on the pivot 21 until the printing character 15 moves into the printing position. The continued downward movement of the key bar causes the underside of the key plate to contact with the underlying part 40 of the adjacent bar and therefore couples both bars 29 and 30 in their action which results in the printing of the selected character.

The printing of any of the characters in the second line of the row A of keys is accomplished by pressing on the key over the selected character. The initial portion of the downward movement of the key bar swings the printing plate to move the printing character 16 into printing position. The key plate then contacts the underlying portion 40 of the adjacent key bar and the final portion of the downward movement of the key bar results in the forward printing movement of the selected character.

When pressure is applied to two keys at their adjacent inner edges both key bars are actuated in unison which results in the printing of the characters 17 on the printing member.

The printing of the characters in the line 2 of row B (B, K, G, L, etc.) is accomplished by operating the keys in just the same manner as that described in connection with line 1 of row A and results in the printing of the character at 19 being printed, and the printing of the characters in line 1 of row B (F, C, W, R, etc.) is by the same action as that described in connection with line 2 of row A and results in the printing character at 18 being printed.

The printing of the characters on row C of the key plates will now be described. To print the character U the operator presses on the key plate over this character. The initial portion of the downward movement of the key bar swings the printing plate to move the printing character 18 into printing position. The arm 53 then contacts the arm 51 and the final portion of the downward movement of the key bar results in the forward printing movement of the selected character. The application of pressure over the Y character results in the selection and final printing of the character on line 16 of the printing member.

Pressure on the key plate over the character A will cause the key plate to tip lifting the arm 53 into a higher position above the arm 51. The purpose of the tipping is to get the arm 53 out of the way to permit the key bars to be operatively connected by means of the flanges 55 and 56 and the bearing 57. Thus when the pressure is applied over the character A the key bar will move downward causing the printing member to move the printing character 19 into printing position. The flange 55 then contacts the bearing 57 of the adjacent key bar and the final portion of the movement of the key bar results in the forward printing movement of the selected character. The application of pressure above the character E will cause the bearing 57 to move downward causing the letter which appears in line 15 on the printing member to move into printing position. The bearing 57 now contacts the flange 56 of the adjacent key bar and the printing of the selected character results. When both keys are pressed by straddling them with a thumb or finger the character I, which is arranged in line 17 on the printing member will be impressed against the paper strip on the platen.

In a shorthand machine equipped with my key-
75 board where a multiple selective printing is ac-

complished by the co-action of two keyplates certain requirements must be met in the arrangement of the letters, numerals and characters to insure ease of operation and a simple method of writing. As a plurality of types are attached to one printing member it is important that none of these letters so placed will appear together when writing words or syllables. Thus S, T, and R must appear on different key units while V, 10 S, F, B can safely be attached to one and the same printing member as they do not form combinations when writing words and syllables. This method of arrangement has been carried out throughout the keyboard. To promote ease of writing awkward finger positions must be avoided. Letters appearing in the extreme rows should not be printed at the same time. The first row is therefore reserved for numerals. The letters in the fifth row seldom if ever appear in combinations with letters in the second row. The letters 15 most frequently used and which form combinations are found in the three central rows and require only a slight movement of the fingers in operation. The fifth key unit from the left is not used in phonetic writing to avoid unnecessary movement of the left hand. The two units of keys reserved for the vowels are so arranged that a complete series of vowel sounds can be expressed, removing any chance of misreading a word.

What I desire to claim is:

1. In a shorthand typing machine consisting of a plurality of printing members each having a series of printing characters, each of said printing members having a pair of pivoting points placed vertically one above the other and wherein in the upper of said pivoting points consists of a vertically disposed slot, a plurality of actuating bars arranged in pairs with a printing member therebetween, one of said bars of a pair being pivotally connected by a pin to said printing member at one of said pivoting points and the other bar of said pair being pivotally connected by a pin to said printing member at the other of said pivot points, said pins and said pair of pivoting points constituting a coacting connection between each printing member and its pair of associated actuating bars whereby each bar acts as a shift key in its initial movement and as a printing bar in its final movement, and means for actuating either one of said bars to select one of the characters on the printing member and for then rocking said key bars simultaneously to subsequently move the printing member forward to print the selected character.

2. In a shorthand typing machine consisting of a plurality of printing members each having a series of printing characters, each of said printing members having a pair of pivoting points placed vertically one above the other and wherein in the upper of said pivoting points consists of a vertically disposed slot, a plurality of actuating key bars arranged in pairs with a printing member therebetween, one of said bars of a pair being pivotally connected by a pin to said printing member at one of said pivoting points and the other bar of said pair being pivotally connected by a pin to said printing member at the other of said pivot points, said pins and said pair of pivoting points constituting a coacting connection between each printing member and its pair of associated actuating key bars whereby each bar acts as a shift key in its initial movement and as printing bar in its final movement, and means for actuating either one of said bars to select one of the characters on the printing member and

then actuating both of said bars simultaneously to subsequently move the printing member forward to print the selected character, said printing member and said pair of actuating bars being so constructed and arranged that the initial actuating of said one of said bars causes a slower motion of said printing member than the subsequent motion moving the printing member forward to printing position.

3. In a machine of the character described, comprising a plurality of printing members each bearing a series of printing characters, a pair of actuating levers each having a pivotal connection with a printing member arranged therebetween wherein one pivotal connection is vertically spaced above the other, a pair of key bars each operatively connected to one of said actuating levers, and a plurality of keys coupled in pairs to actuate the key bars first individually to cause an initial selection and then jointly to cause a final printing of the characters on said printing member.

4. The subject matter of claim 3 and, said keys and key bars being constructed and arranged in such a manner that an overlapping connection is provided between one key bar and the key of the other key bar.

5. The subject matter of claim 3 and, the bars comprising each pair of key bars having an overlapping connection for joint action after a predetermined movement of one of said bars.

6. In a typing machine consisting of a plurality of printing members each having a series of characters peripherally spaced on its surface, a plurality of actuating levers arranged in pairs with a printing member therebetween, said levers being independently pivotally connected to said printing member, and means for actuating one of said levers to select one of the characters on the printing member and then actuating all of said levers to subsequently move the printing member forward to print the selected character, the pivotal connections between said levers and printing member being spaced one above the other and the pivot of one pivotal connection occupying a vertically disposed slot.

7. In a machine of the kind described, comprising a plurality of printing members each bearing a series of printing characters, a pair of levers an arm of each of which has a pivotal connection with a printing member arranged therebetween, the pivotal connection between one arm and the printing member being vertically arranged above the other pivotal connection between the other arm and the printing member, a pair of key bars each having a connection with a finger of one of said levers, and a plurality of keys coupled in pairs to actuate the key bars and in turn the levers individually through the medium of said fingers to cause an initial selection and then jointly to cause a final printing of the characters on said printing member.

8. The subject matter of claim 7 and, said keys and key bars being constructed and arranged in such a manner that an overlapping connection is provided between one key bar and the key of the other key bar.

9. The subject matter of claim 7, and said key bars each having an overlapping connection for joint action after a predetermined movement of one of said bars.

10. In a machine of the kind described, comprising a platen, a plurality of printing members each provided with a plurality of types arranged in a vertical position facing said platen and mov-

able in a horizontal direction to cause said types to print on paper supported by said platen, said printing members each having two independent pivot points a line drawn through which extends parallel to the printing line of said types, a pair of key bars, a plurality of keys coupled in pairs to actuate the key bars individually or jointly to initially select and subsequently print one of the types on said printing member, and connecting means between said key bars and each printing member to perform the function ascribed to actuation of the key bars, said connecting means comprising a pair of bell crank levers one of which has an arm pivoted at one of said pivot points and the other of which has an arm pivoted at the other of said pivot points.

11. In a shorthand typing machine consisting of a plurality of printing members each bearing a series of printing characters, a plurality of key bars arranged in pairs and connected to said printing members, the bars in each pair having an overlapping connection for joint action after a predetermined movement of one of said bars, and key members associated with each key bar, said key members being arranged in a parallel closely spaced relation transversely of the machine whereby transverse parallel adjacent edges thereof may be simultaneously depressed at their midlength portions by a finger of the operator to cause the printing of one of the characters of the associated printing member.

JOHN L. STIXRUD.
